UNITED STATES PATENT OFFICE

118,814

DESIGN FOR A REFRIGERATOR CABINET

Donald E. Dailey and Harold Van Doren, Toledo, Ohio, assignors to Philco Refrigerator Company, Philadelphia, Pa., a corporation of Delaware

Application December 2, 1939, Serial No. 88,640

Term of patent 14 years

To all whom it may concern:

Be it known that we, Donald E. Dailey and Harold Van Doren, citizens of the United States, residing in Toledo, Lucas County, State of Ohio, have invented a new, original, and ornamental Design for a Refrigerator Cabinet, reference being had to the accompanying drawing, forming part thereof, in which the single figure is a perspective view of a refrigerator cabinet showing our design.

We claim:

The ornamental design for a refrigerator cabinet, substantially as shown.

DONALD E. DAILEY.
HAROLD VAN DOREN.
